McKinstry Grable(57) **CLAIM**

The ornamental design for a joystick, as shown and described.

DESCRIPTION

FIG. 1 is a perspective view of a joystick showing my new design;

FIG. 2 is a rear view of the design thereof;

FIG. 3 is a front view of the design thereof;

FIG. 4 is a side view of the design thereof;

FIG. 5 is a side view of the design thereof showing the side opposite of the joystick side shown in FIG. 4; and,
FIG. 6 is a top view of the design thereof.

The broken lines in the drawings are included to illustrate portions of a boot and base to support the joystick and form no part of the claimed design.
